UNITED STATES PATENT OFFICE.

LEONARD E. ASKE, OF DULUTH, MINNESOTA.

ELECTRIC HEATER OR FUMER.

Application filed June 19, 1924. Serial No. 720,994.

My invention relates to electric heaters, vaporizers or fumers and has for its object the provision of an improved device of the type referred to, for converting hydro-carbon fuel into fumes for internal explosion engines. With this and other objects in view, it consists of the structures, combinations and arrangements of parts hereinafter described and claimed.

10 In the drawings, Fig. 1 is an end elevation, partly in central vertical section of one form of a fuel-mixture conduit, embodying my said invention. Fig. 2 is a top view of the hereinafter described heating element embodied in my said invention. Fig. 3 is 15 a top plan view of said conduit, and Fig. 4 is a side elevation of said conduit.

In the drawings, 1 is a conduit for conducting air and hydrocarbon fuel from any 20 suitable sources to the cylinder or cylinders of an internal explosion engine (not shown). Said conduit is provided with an air intake end 1^a; a mixing chamber 1^b for mixing the air with hydrocarbon fuel, vapor or 25 fumes, a discharge nozzle 1^c, adapted to be connected to the valve chamber, or intake port of an engine cylinder (not shown). Said conduit is also provided with a suitable fuel intake port 1^d, to which is connected a 30 fuel supply pipe 2. Said conduit is further provided with a heating chamber 3 having a fuel intake port 3^a to which is connected a branch fuel supply pipe 2^a, in which latter is preferably interposed a regulating or cut-off valve 2^b, of any suitable structure.

Within said heating chamber is positioned a heating element comprising a binding post 4 adapted to conduct electricity; a core 5 of suitable refractory insulating material, as 40 porcelain, through which said post extends longitudinally; said core being reduced in external diameter for a portion of its length, as at 5^a; a resistant conductor of electricity as a wire resistance coil 6 connected to said 45 post and closely encircling said core; an insulation sleeve 7, of any suitable insulating material, as mica, encircling the enlarged portion of said coil and extending above the same; a metal case 8 encircling said sleeve; 50 a metal contact thimble 9 encircling the portion of said coil at the reduced end of said core in contact with the reduced portion of said coil and spaced from the side wall of said chamber; a filling plug of refractory cement 10 for the upper end of said sleeve;

and an adjustable contact point 11 extending through the wall of said heater chamber and contacting with the thimble 9. Extending through said filling 10 are a plurality of ports 12 in registration with the coil 6. 60

It will be observed that an annular space 13 is formed between the thimble 9 and the wall of said heating chamber which space communicates with the coil space between the enlarged portion of said cylinder and 65 said mica cylinder. Said annular space is adapted to operate as a reservoir for hydro-carbon fuel supplied by said pipe 2^a through said port 3^a.

If desired, said mixing chamber may be 70 primed through a port 14, adapted to be closed by a plug 15. One end of said post extends outwardly of said heating chamber and forms one terminal of said heating element, the other terminal of which is 75 grounded on said chamber by said contact point.

The heating element is primarily designed for heating, vaporizing and fuming hydro-carbon fuel for starting the engine when the 80 cylinders and adjacent parts are cold. The coil of the heating element is therefore preferably interposed in the motor circuit of an electric engine operating device, not shown, but well known to the art; or in a lighting 85 circuit, not shown but well known to the art. It may however be in an independent circuit, and may be operated as long as desired before and after starting the engine. 90

In operation, when the engine is cranked 90 or turned over, a partial vacuum is formed in said conduit, thereby causing air to be drawn into said mixing chamber through the air intake end of said conduit, and fuel oil to be drawn into said mixing and heat- 95 ing chambers through the pipes 2 and 2^a, respectively. The oil drawn into said heating chamber is drawn up through the coil space therein in contact with the highly heated electric coil and in contact with the 100 heated porcelain core and the heated mica sleeve and is promptly converted by the heat into dense fumes which escape through the ports in said filler 10 into said mixing chamber, where it is mixed with air and drawn 105 out into the engine cylinder or cylinders. After the cylinders and adjacent parts are well heated, the coil 6 may, if desired be cut out of circuit, and the valve closed.

My said invention is especially desirable 110

for vaporizing or fuming comparatively heavy fuel oils, such as kerosene; but is also highly efficient in fuming gasoline.

It is obvious that my said invention may 5 be modified or altered in various particulars within the spirit and scope of my claim.

What I claim is:

The combination of a binding post adapted 10 to conduct electricity; a core of refractory insulating material encircling said post intermediate of its ends, said core being reduced in diameter at its lower end; a resistance coil electrically connected at one end with said post and wound closely around 15 said core and grounded at its opposite end; a sleeve of refractory insulating material closely encircling the enlarged end of said

coil and extending above the same; a metal thimble closely encircling and in contact with the reduced end of said coil, said thimble being of shorter external diameter than 20 said insulating sleeve; a metal sleeve encircling said insulating sleeve; a filling of refractory material within the portion of said sleeve above said core, said filling having a 25 plurality of ports therein; and means adapted to conduct fluid to be heated to the coil space between the enlarged portion of said core and the insulation sleeve encircling the 30 enlarged portion of said coil.

In testimony whereof, I hereunto affix my signature.

LEONARD E. ASKE.
